UNITED STATES PATENT OFFICE

154,794

DESIGN FOR A HOLDER FOR SMOKERS' PIPES

Paul L. Ogden, New York, N. Y.

Application May 20, 1948, Serial No. 146,486

Term of patent 7 years

(Cl. D85—8)

To all whom it may concern:

Be it known that I, Paul L. Ogden, a citizen of the United States of America, residing in the city of New York and the county of New York and State of New York, have invented a new, original, and ornamental Design for a Holder for Smokers' Pipes, of which the following is a specification, reference being had to the accompanying drawing, forming part thereof.

I claim:

The ornamental design for a holder for smokers' pipes, as shown.

PAUL L. OGDEN.
